Primary Examiner — Jennifer Rivard(74) *Attorney, Agent, or Firm* — Marshall, Gerstein & Borun LLP(57) **CLAIM**

The ornamental design for a lipstick container, as shown and described.

DESCRIPTION

FIG. 1 is a perspective view of a lipstick container, showing the new design.

FIG. 2 is a front elevation view of the lipstick container.

FIG. 3 is a right-side elevation view of the lipstick container.

FIG. 4 is a left-side elevation view of the lipstick container.

FIG. 5 is a right-side elevation view of the lipstick container.

FIG. 6 is a top plan view of the lipstick container; and,

FIG. 7 is a bottom plan view of the lipstick container.

The broken lines represent elements of the container for cosmetics that form no part of the claimed design.

The intermediate section of the lipstick container is transparent or translucent, permitting the interior structure to be visible.
